UNITED STATES PATENT OFFICE

JOHN M. ROELFING, OF PLAINFIELD, NEW JERSEY, ASSIGNOR TO AMERICAN CAR AND FOUNDRY COMPANY, OF NEW YORK, N. Y., A CORPORATION OF NEW JERSEY

CUPOLA-CHARGING BUCKET

Application filed June 17, 1929. Serial No. 371,429.

This invention relates to material handling devices and has particular reference to a charging device for cupola furnaces.

One object of the present invention is the provision of a bucket for charging cupolas. Another object of the invention is the provision of a cupola charging bucket which, when the doors are unlocked, will provide a full opening without obstruction to the flow 10 of material.

Another object of the invention is the provision of a cupola charging bucket in which internal door holding links are eliminated.

The invention also contemplates the provision of a mechanism in which the bucket per se is, in effect, independent of the operating means for opening the doors and yet is not entirely detached but will, due to the fact that its weight is greater than the weight 20 of the doors, tend to partially close the doors so that when the bucket is set on rails or the floor, the doors will close and the latches will lock the doors until such time as the bucket operator decides to open them.

25 A further object of the present invention is the provision of a bucket with drop-bottom doors and operating means for the latter which will permit the operator to open the doors at any point between the picking up point and the hoisting point to which the bucket is raised.

30 A still further object of the invention is the provision of a hoisting bucket with drop-bottom doors connected thereto to close the open lower end thereof, or the discharge opening; said doors being connected to the bucket in such a manner as to swing entirely clear of the bucket to permit an unobstructed discharge of the material carried 40 by the bucket.

45 A still further object of the invention is the provision of a charging device for cupola furnaces including a bucket, in which the weight of the latter is utilized to return the drop-bottom doors thereof to partially closed position.

50 As another object, the invention contemplates the provision of locking means for the doors of a cupola charging bucket, which

locking means are entirely independent of the door actuating mechanism.

Another object of the invention is the provision of a cupola charging bucket which is formed of few parts and which is strong 55 and durable in construction.

Other objects and advantages of this invention will be apparent from the following description taken in conjunction with the accompanying drawings, in which:

60 Figure 1 is a side elevation of the device of the present invention, certain parts being shown in section;

Fig. 2 is an end elevation of the device, certain parts being shown in section;

65 Fig. 3 is a partial top plan view of the bucket of the present invention, showing also, in plan, one of the bucket hangers;

Fig. 4 is a sectional view on the line 4—4, 70 Fig. 1;

Fig. 5 is an inverted plan view of the bail shown in Fig. 1;

Fig. 6 is a fragmentary view of the bucket and its bail, certain parts being shown in section; the view also showing in broken 75 lines the doors in partly open position;

Fig. 7 is a sectional view of a portion of the device, one of the doors being shown in fully open position; and

Fig. 8 is a sectional view on the line 8—8 80 of Fig. 2.

Referring now more particularly to the drawings, in which similar characters of reference designate similar parts in the several views, the material handling device of the present invention comprises generally a bucket A, bucket hangers B, bail C, doors D and door hinge links E.

85 As can be clearly seen in the drawings, the bucket A is formed of flanged side and end walls 2 and 4 respectively, the flanges 6 of which are adjacently arranged and connected together by suitable fasteners such as the bolts 8.

To provide additional strength to the 95 bucket, the side and end walls may be provided with horizontally arranged ribs 10 which, when the side and end walls are so connected, are alined, as shown clearly in Fig. 2. The side walls 2 are of the form 100

shown clearly in Fig. 3, having the side edges thereof curved as shown at 12. Secured to said side edges 12 are fulcrum lugs 14 having elongated openings 15 in which a shaft 16 is mounted, the latter being restrained against horizontal shifting by suitable means such as the pins 18. The shaft 16 serves to mount a fulcrum barrel 20 which is a part of the bucket hanger B. 10 The description herewith pertains to one end of the bucket, but it is to be understood that the construction is duplicated on the other end of the bucket and a description of one end (Figs 2 and 3, for example) 15 will suffice for both.

The bucket hanger B also includes the spaced arms 22, preferably formed integral with the barrel 20, and which arms extend upwardly and have secured to the upper end 20 thereof by a bolt 24 and by keys 25 (see Fig. 8), a hook 26. The shank of the hook extends between the upper ends of the arms 22 and is provided with a lifting head 29 to take the load, as will be apparent. The 25 hooks 26 at each end of the bucket are suspended from links 28 which are pivotally connected as at 30 to the lower ends of lifting cables 32. To permit suspension of the hangers B, the links 28 are provided with 30 elongated openings 34 into which the hooks 26 may be readily inserted. The links 28 are pivotally connected to the bail C, as presently to be described.

The particular construction of the bail 35 is shown more clearly in Figs 4 and 5, where it can be seen that the same comprises the spaced side pieces 36 which are connected to end spacers 38 by any suitable means, such as by welding. The links 28 are arranged between the pieces 36 and are pivotally connected thereto by the pins 40. Secured to the side pieces and arranged therebetween are abutments 42 for positioning the links 28 or for preventing excessive 45 shifting of the latter whereby said links are normally retained in the position shown in Fig. 1.

The side pieces are spaced further apart at their centers than at the ends thereof 50 (see Figs. 4 and 5) and spacers 44 are connected thereto as by being welded to said side pieces. In each of the angles defined by the spacers 44 and the side pieces 36, blocks 46 are secured which serve as guides 55 for a weight 48, as will be apparent from an inspection of Fig. 4. The weight 48 is suspended by a weight lifting cable 50 by means of a pivot joint 52, and adjacent the lower end of the weight lugs 54 are provided 60 which are adapted to contact with abutments 56 secured between the side pieces 36 and adjacent the spacers 44 whereby to limit the upward movement of the weight 48, as shown in Figs. 6 and 7.

65 The links 28, heretofore described, are

connected to the weight 48 by means of a toggle comprising the arms 58 pivoted to the lower end of the weight at 60 and to the links 28 at 61. It can be seen at this point that, when the weight 48 is lifted by means 70 of the cable 50, the arms 58 will pull the hangers B toward each other (see Figs. 6 and 7) thereby rotating or rocking the barrel 20 on the shaft 16, and when tension 75 on the cable 50 is released the weight 48 will drop thus restoring the toggle to its normal position and returning the links 28 (and hence the hangers B) to their normal position, such as shown in Fig. 1.

As shown in Fig. 2, the barrel 20 is provided with several depending arms 62 at the lower ends of which are formed hinge lugs 64 engaged with a hinge shaft 66, which latter is supported in lugs 68 formed at the rear edge of the door D; the latter (door D) comprising the web 70 and the depending reinforcing ribs 72, as shown in Fig. 6. The rear edges of the doors D are also provided with fulcrum lugs 74 each arranged adjacent one of the lugs 68, and these lugs 74 with their adjacent lugs 68 each support a pin 76 to which the lower ends of raising links 78 are connected. The links 78 extend upwardly adjacent the end walls of the bucket and their upper ends are connected to the bucket through the medium of pins 80 arranged in elongated openings 82 formed in lugs 84.

Each door D is provided with locking lugs 86 which extend beyond the limits of the door and are so arranged as to be engaged by external hooks 88 pivoted on pins 90 carried by the side walls of the bucket, as more clearly shown in Figs. 1 and 2. Two such hooks or latches 88 are provided at each side of the bucket, as will be obvious, and they are normally urged away from each other; or to be more exact, to door supporting position by a spring 92 arranged therebetween. In practice, the hooks are 100 preferably contained in a housing formed by a flange 94 integral with the side wall and having oppositely arranged stops 96 for positioning the hooks (see Fig. 1). For completing the housing, a cover plate 98 is 105 provided which is secured to the flange 94 by screw bolts 100. For supporting the hooks within the housing just described, it has been found practical to support the pins 90 not only by the side wall but also by 110 the cover plate 98, as shown clearly in Fig. 2.

From the above description, it is believed that the operation of the device of the present invention will be apparent to those skilled in the art, but a brief resume thereof is given herewith.

Figure 1 shows the device in normal position with the doors D held closed by the hooks or latches 88. Let us assume that it 120

is desired to dump the contents of the bucket when the latter is in the position illustrated in Fig. 1. There is no appreciable tension on the cable 50 and the bucket is held in suspension by the lifting cables 32. A pull on the cable 50 will force the toggle links 58 to the position shown in Figs. 6 and 7, thereby swinging the links 28 on their pivots 40 and urging the opposed hangers B toward each other. This movement of the hangers B toward each other will rock or rotate the fulcrum barrel 20 on the shaft 16 and transmit movement to the hinge lugs 64. This movement just described will result in a pivoting or swinging of the hanger B, pulling the hinge lugs 64 outwardly, or in other words, forcing the hinge lugs 64 away from each other and shifting the doors transversely of the discharge opening; the doors thus being pulled away from each other and away from their supported connection with the latches 88. It can be seen here that no movement of the hooks takes place during this operation. When the lugs 86 have been freed from their engagement with the latches 88, it will be apparent that the doors will swing downwardly by gravity in the absence of any load in the bucket. Of course, with a load in the bucket the downward movement of the doors D is accelerated and, as the doors drop, the load immediately drops from the bucket and the impact of the load against the doors forces the doors to the position shown in Fig. 7. As the doors approach the position shown in Fig. 7, due to the impact of the load thereagainst the doors rotate about the shaft 66, this rotation forcing the pins 76 and their lugs in an arc upwardly, thus forcing the raising links 78 upwardly in the openings 82; this motion continuing and urging or forcing the bucket A upwardly with respect to the hangers B, as shown in Fig. 7. After the load has been discharged and the impact or weight thereof is not against the doors D, the weight of the bucket becomes effective then to return the doors to partially closed position. The doors being much lighter in weight than the bucket, they will not offer sufficient resistance through the raising links 78 to maintain the bucket in the elevated position shown in Fig. 7 and the extra weight of the bucket therefore will force the pins 80 downwardly and thus urge the doors to the position shown in broken lines in Fig. 6; or in other words, the downward motion of the bucket will partially close the doors D. The cable 50 is only actuated to break the toggle connection, as will be apparent, and the pull on the cable 50 having been released, when the operator lowers the bucket to the floor the doors D will be forced toward their closed and locked position and the

links 28 will be forced to their normal position (due to the lowering of the weight 48) thereby shifting the hangers B to the normal position shown in Fig. 1 and urging the doors transversely so that the lugs 86 may be engaged with the latches 88.

The drawings herein illustrate one embodiment of the present invention, but it is to be understood that these drawings are for illustrative purposes only and that various changes in the form and proportions of the device may be made within the scope of the appended claims without departing from the spirit of the invention.

What is claimed is:

1. In a cupola charging bucket having a discharge opening, doors normally closing said opening and adapted to open by gravity and to be automatically partially closed by the weight of the bucket.

2. In a cupola charging bucket having a discharge opening, horizontally shiftable doors hingedly connected with the bucket and adapted to swing to open position by gravity, and means for utilizing the weight of the bucket for returning the doors to partially closed position comprising means connecting the bucket and doors.

3. A bucket having a discharge opening, a door for the discharge opening, means for operating the door to discharge the bucket, means for supporting the bucket for substantially vertical movement relative to the supporting means, and means for utilizing some of the energy of the descending charge for raising the bucket relative to the supporting means.

4. In a cupola charging bucket having a discharge opening, horizontally shiftable doors hingedly connected with the bucket and adapted to swing to open position by gravity, and means for utilizing the weight of the bucket for returning the doors to partially closed position comprising rigid elements connecting the bucket and doors and shiftable by the doors under the impact of the load being discharged to exert a thrust against the bucket to elevate the latter and to be actuated by the bucket after the load has been discharged.

5. A cupola charging bucket having a discharge opening, doors normally closing said opening and mounted to swing to partially open position by gravity and to fully open position under impact of the load being discharged, and actuating elements connecting the bucket and doors to be operated by the doors under the impact of the load being discharged and to be actuated by the bucket after the load has been discharged to return the doors to partially closed position.

6. A cupola charging bucket having a discharge opening, horizontally shiftable doors hingedly connected with the bucket and normally closing the discharge opening, said

- doors being adapted to open by gravity and to be urged to closed position by the weight of the bucket.
7. In a cupola charging bucket, hangers pivotally secured thereto for supporting said bucket, doors pivotally secured to the hangers, means for retaining the doors in closed position, and means connecting the hangers for actuating the latter on their pivots to free the doors from their retaining means. 10
8. In a cupola charging bucket, hangers pivotally secured thereto for supporting said bucket, doors pivotally secured to the hangers, means for retaining the doors in closed position, and means connecting the hangers for actuating the latter on their pivots to shift the doors transversely away from each other, to free the doors from their retaining means to permit them to shift on their 20 pivots.
9. A bucket having a discharge opening, a door for the discharge opening, a pivotal mounting for the door, retaining means with which the door is engaged for holding the door in closed position, and a toggle mechanism for moving the door transversely of the opening to free the latter from the retaining means to permit the door to swing open by gravity.
- 30 10. The combination with a bucket having a discharge opening, of a pivotal support for said bucket, a door for the discharge opening pivotally connected to the pivotal support and arranged to swing to open position by gravity, a slid able connection between the pivotal support and the bucket, and means operable upon swinging movement of the door for moving the bucket with respect to said pivotal mounting.
- 40 11. A cupola charging bucket having a discharge opening, doors normally closing the opening, supporting means for the bucket connected to the latter, said doors being pivotally connected to said supporting means, and means for shifting the supporting means whereby to actuate the doors transversely of the discharge opening to permit said doors to swing on their pivots.
- 50 12. In a device of the kind described, a bucket having an open lower end, doors normally closing the open end, supporting means for the bucket pivotally connected to the latter, hinge means connecting the doors with said supporting means, links 55 connecting the doors and bucket, and means for shifting the supporting means on their pivots to actuate the doors horizontally whereby they may swing on their pivots to uncover the open ends and actuate the links to raise the bucket relative to the supporting means.
- 60 13. A cupola charging bucket having a discharge opening, doors normally closing said opening, and means for supporting the 65 doors comprising bucket supporting hangers pivoted to the bucket and hingedly connected to the doors, means for retaining the doors in closed position, said hangers being shiftable on their pivots to move the doors horizontally of the discharge opening to free the same from their retaining means and to dispose the hinge connection outside the discharge opening whereby the doors will swing clear of the discharge opening. 70
14. A material handling device of the kind described comprising a bucket having drop-bottom doors, hangers for the bucket to which the doors are hingedly connected, a bail, hoisting links connected to the bail and to which the hangers are secured, a toggle connecting the links, and means for actuating the toggle to move the hangers simultaneously whereby to shift the doors horizontally. 75
15. A material handling device of the kind described comprising a bucket, drop-bottom doors for the bucket, hangers for the bucket connected to the doors, latches for holding the doors in closed position, said hangers being shiftable whereby to actuate the doors horizontally to free the latter from the latches. 80
16. A material handling device of the kind described comprising a bucket, drop-bottom doors for the bucket, hangers for the bucket pivotally connected to the doors, latches for holding the doors in closed position, and means for shifting the hangers on their pivots whereby to actuate the doors 85 to free the latter from their latches.
17. A bucket having a discharge opening, means for supporting the bucket for substantially vertical movement relative to the supporting means, a door for the discharge opening, and means effective upon opening the door for raising the bucket relative to the supporting means. 90
18. A bucket having a discharge opening, a lever, means cooperating with the bucket to provide a movable fulcrum for the lever, the movable fulcrum being arranged to support the bucket from the lever for substantially vertical movement relative to the latter, a door for the discharge opening pivotally mounted on an arm of the lever, means secured to the bucket for normally holding the door in closed position, means for operating the lever to move the door transversely of the discharge opening to free the same from its connection with the door holding means whereby the door may swing on its pivotal mounting to open position, and means responsive to the swing of the door for raising the bucket substantially 95 vertically relative to the lever. 100
19. A bucket having a discharge opening, a lever, means cooperating with the bucket to provide a movable fulcrum for the lever, the movable fulcrum being arranged to 105
- 130

support the bucket from the lever for substantially vertical movement relative to the lever, a door normally closing the discharge opening and pivotally mounted on an arm of the lever, an arm on the door projecting outwardly beyond the pivotal mounting thereof, a link pivotally connected to the second-named arm and slidably connected to the bucket, latches for holding the door in closed position, said lever being operable to move the door transversely of the discharge opening whereby the door is freed from the latches and may swing to open position by gravity, said second-named arm and said link being operable during the swing of the door to raise the bucket substantially vertically relative to said lever.

20. In a bucket of the kind described, hangers pivotally secured to the bucket for supporting the latter, bottom doors pivotally secured to the hangers, and supporting means for retaining the doors in closed position, said doors being horizontally shiftable upon pivotal movement of the hangers, whereby to free them from the supporting means.

21. A cupola charging bucket having a discharge opening, doors normally closing the opening, supporting means for the bucket connected to the latter, said doors being pivotally connected to said supporting means, and means for shifting the supporting means whereby to actuate the doors transversely of the discharge opening to permit said doors to swing on their pivots entirely free of the door opening.

22. A cupola charging bucket having a discharge opening, doors normally closing said opening and mounted to swing to partially open position by gravity and to fully open position under impact of the load being discharged, and bucket actuating elements connecting the bucket and doors.

23. A cupola charging bucket having a discharge opening, doors normally closing said opening and mounted to swing to partially open position by gravity and to an open position outside of the door opening under impact of the load being discharged, and bucket actuating elements connecting the bucket and doors.

24. A cupola charging bucket having a discharge opening, doors normally closing said opening and mounted to swing to partially open position by gravity and to an open position outside the plane of the door opening under impact of the load being discharged, and actuating elements pivotally secured to the doors and pivotally and slidably connected to the bucket for exerting a thrust against the bucket when the doors approach fully open position under impact of the load being discharged, whereby when impact against the doors is relieved upon complete discharge from the bucket, the weight

of the bucket will force the doors to partially closed position.

25. A device of the kind described, comprising a bucket having a discharge opening, hinged doors normally closing the discharge opening and adapted to swing to open position by gravity, supporting means for the bucket, and rigid elements slidably connecting the doors and bucket for transmitting power from the doors during the swing thereof to the bucket for raising the latter relative to the supporting means, whereby some of the energy imparted to the doors by the descending load from the bucket may be utilized for raising the latter to permit descent of the bucket relative to the supporting means for partially closing the doors.

26. A bucket having a discharge opening, supporting elements for the bucket connected thereto by a slidable connection to permit substantially a vertical movement of the bucket relative to the supporting means, a door for the discharge opening, and slidable connections between the door and bucket effective only as the door approaches its fully open position for raising the bucket relative to the supporting means.

27. A cupola charging bucket having a lower open end, doors normally closing said open end, and means for supporting the doors comprising bucket-supporting hangers pivoted to the bucket and hingedly connected to the doors, said hangers being shiftable on their pivots to move the doors horizontally to dispose the hinge connection outside the discharge opening, whereby the doors will swing clear of the discharge opening.

28. A cupola charging bucket having a discharge opening, doors for said opening, latches normally retaining the doors in closed position, hangers pivotally secured to the bucket for supporting the latter, said hangers being hingedly connected to the doors, and means for shifting the hangers on their pivots to free the doors from the latches and to place the hinged connection of the doors outside the discharge opening, whereby to permit the doors to swing entirely clear of the discharge opening.

29. In a cupola charging bucket having a discharge opening, horizontally shiftable doors hingedly connected with the bucket and adapted for horizontal shifting to swing to open position by gravity, and means for utilizing the weight of the bucket for returning the doors to partially closed position comprising rigid elements pivotally secured to the doors and pivotally and slidably connected to the bucket.

30. In a cupola charging bucket having a discharge opening, doors hingedly connected with the bucket and adapted to swing on their hinges to open position by gravity, said doors being horizontally shiftable in

substantially a straight line prior to their swinging movement.

31. In a cupola charging bucket having a discharge opening, doors hingedly connected with the bucket and adapted to swing on their hinges to open position by gravity, said doors being horizontally shiftable in substantially a straight line prior to their swinging movement, and means for utilizing the weight of the bucket for returning the doors to partially closed position, comprising means connecting the bucket and doors.

In witness whereof I have hereunto set my hand.
